WILLIAM D. HAWLEY, OF SYRACUSE, NEW YORK

INDICATING CRYSTAL FOR TIMEPIECES

Application filed September 2, 1927. Serial No. 217,109.

This invention relates to clocks, watches and other time pieces and has for its object a particularly simple and efficient adjustable indicating crystal by which the elapsed time can be readily indicated or by which both day-light saving and standard time or other times as eastern and central time is indicated by the time piece.

The invention consists in the novel features and in the combinations and constructions hereinafter set forth and claimed.

In describing this invention the invention reference is had to the accompanying drawings in which like characters represent corresponding parts in all the views.

Fig. 1 is an enlarged plan view of a watch provided with my invention.

Fig. 2 is a fragmentary sectional view of the device taken on the line 2—2 of Figure 1.

Fig. 3 is an enlarged fragmentary detail view of the device shown in Fig. 1.

Fig. 4 is a fragmentary view illustrating the fluted margin of the rotatable crystal shown in Figs. 2 and 3.

Fig. 5 is a fragmentary detail view of a modified form of the crystal.

This invention comprises a time piece having a rotatable crystal consisting of inner and outer layers in surface contact with each other, the outer layer being provided with graduations and is rotatable on the inner layer into a predetermined position to the time graduations on the face of the time piece.

1 designates the time piece including the usual case.

2 designates the bezel ring which holds the crystal.

3 designates the inner layer of the crystal, which is usually glass.

4 designates the outer layer rotatably mounted on the inner layer 3.

5 designates a circle of graduations on the outer layer and arranged concentric with the crystal. The layer 4 is celluloid or some other material. Celluloid can be readily provided with graduations or indications while it is difficult and expensive to provide

because of the liability of glass crystals breaking.

It is impractical to stencil, sand blast, etch, or print on glass crystals. It is also impractical to use molded glass crystals with graduations thereon as the molded glass crystals with the indications thereon would be prohibitively thick. Celluloid crystals alone detract from the appearance of the time piece or watch. The crystal may be provided with more than one circle of time graduations or indications as an inner circle 6.

The outer circle 5 is graduated into hours and fractions thereof indicating tenths of an hour, that is, periods of 6 minutes and coacts with the hour hand of the timepiece. The inner circle 6 is graduated into minutes and coacts with the minute hand of the time piece.

Assuming that it is desired to time an event which begins at nine o'clock, the outer layer of the crystal is turned until the zero graduations on the crystal are in line with the nine o'clock graduations on the face of the timepiece. The hands of the clock, of course, indicate nine o'clock.

In Fig. 1, the position of the hands indicates when the event was completed. Taking the reading on the hour hand circle 5, which is divided into graduations representing tenths of hours or intervals of six minutes, the reading is two and one tenth hours, or two hours six minutes. For long periods, the crystal is set with the zero graduations in line with the hour hand and the reading taken from the outer circle 5. For short periods which take less than one hour, the zero graduations are set in line with the minute hand and the reading taken from the minute or inner circle 6.

In Fig. 1, the reading on the minute circle 6 shows elapsed time of twenty-two minutes of an event started when the minute hand was at a quarter to nine o'clock.

In Figs. 1, 2 and 3, the inner glass layer 3 is fixedly mounted in a bezel ring 2 and the outer layer 4 rotatably mounted on the glass layer 3, with its margins extending into a channel or rabbet 8 in a metal ring 9 which

is fastened preferably by an adhesive to the margin of the glass layer 3.

In order to hold the layer 4 in its adjusted position, the margin thereof in the rabbet may be fluted as shown in Fig. 4. Also, to facilitate the turning of the outer layer 4, said layer is provided with a boss or finger engaging portion 10. As the ring 9 might cover the minute graduations on the face of the time piece, minute graduations 11 are provided on the ring 9.

In Fig. 5, the outer layer 4a is rotatably mounted on the inner layer 3a by having its margin 12 bent around the edge of the inner layer 3a. In this construction, the glass layer 3a is made a little smaller in diameter than usual to fit the bezel ring 7a and the bent over margin 12 of the outer layer 6 extends into the groove in the bezel ring so that the entire crystal fits the bezel ring sufficiently to hold the crystal in position and permit rotation of the outer layer 4a.

In this construction, it is immaterial whether or not the inner layer also rotates when the outer layer is rotated.

By my invention, any watch or clock can be readily provided with an indicating crystal for indicating elapsed time periods, standard and daylight saving time, etc.

What I claim is:

In a timepiece having crystals including inner and outer layers and a bezel ring, the outer layer being rotatable and provided with indicating characters and the inner layer being mounted in the bezel ring of the timepiece and a ring fixed on the inner layer and having a rabbet for receiving the margin of the outer layer.

In testimony whereof, I have hereunto signed my name at Syracuse, in the county of Onondaga and State of New York, this 31st day of August, 1927.

WILLIAM D. HAWLEY.
